BOTTLE

Roger P. Musson, King County, Wash., assignor to Tree Top Incorporated, Selah, Wash., a corporation of Washington

Filed Jan. 31, 1969, Ser. No. 15,579

Term of patent 14 years

Int. Cl. D9—01

U.S. Cl. D9—92

FIG-1

FIG-4

FIG. 1 is a side elevational view of a bottle embodying my new design, the bottle having the same appearance from all sides;

FIG. 2 is a fragmentary detail elevational view thereof;

FIG. 3 is a fragmentary detail cross-sectional view thereof taken on line 3—3 of FIG. 1;

FIG. 4 is a fragmentary detail vertical sectional view taken on line 4—4 of FIG. 2; and

FIG. 5 is a top plan view thereof.

I claim:

The ornamental design for a bottle, substantially as shown and described.
